UNITED STATES PATENT OFFICE.

JOSEPH GOULDBOURN AND FRANK BYCROFT KEALL, OF LEICESTER, ENGLAND, AS
SIGNORS TO UNITED SHOE MACHINERY CORPORATION, OF PATERSON, NEW JER-
SEY, A CORPORATION OF NEW JERSEY.

STAMPING MACHINE.

Application filed December 4, 1922, Serial No. 604,774, and in Great Britain January 7, 1922.

This invention relates to presses and is herein shown as embodied in a machine for stamping or impressing work pieces, such as shoe soles, with identifying symbols. 5
5 Sole leather varies appreciably in thickness and in density or hardness, and in stamping machines that take no account of these characteristics, symbols impressed on different pieces of work are not uniform in 10 appearance or depth. An object of this invention is to provide an improved machine for applying uniform impressions to work pieces having varying characteristics especially as to thickness. As a feature of the 15 invention, the work pieces are always gripped with a uniform pressure between two co-operating pressure members one of which has a preliminary work gripping or measuring movement under spring control, 20 there being a subsequent positive movement of said member for a predetermined distance to effect an impression of the desired depth. In the illustrated embodiment of the invention, the head has a projecting stud for the 25 reception of interchangeable type wheels, there being a swinging latch on the head engaging the end of the stud to lock the wheels in position so that the latter can be quickly removed and replaced by others. 30
The illustrated type head, which is normally locked, has a trunnion mounting in the end of an overhanging arm, the trunnion being first movable endwise to effect unlocking after which the head is rotatable through 35 180° to invert the symbols so that they may be applied either way up on a piece of work. These and other features, advantages and objects of the invention will appear from a consideration of the following specification 40 and accompanying drawings in which:—

Fig. 1 is a side elevation, with some parts in section, of the machine.

Fig. 2 is a detail view of a portion of the driving mechanism.

Fig. 3 is a side view of the printing head with some parts in section.

In the illustrated machine, the printing head is normally in a fixed position so that there is no rapidly moving part directly in front of the operator to distract or oppress him; the main clearance movement takes place from below and the work is pressed upwardly against type wheels on the printing head. A frame 2 has an overhanging

arm 4 in the forward end of which is a cylindrical opening 6. The printing head comprising a bracket 8 has a vertical trunnion 10 swivelled in the opening 6 and having an extension 12 rotatably mounted in a flanged bushing 14 at the top of the overhanging arm. The extension 12 is threaded at its upper end for the reception of a hand nut 16 by means of which a flat face 18 on the printing head may be drawn tightly against a corresponding face on the under side of the overhanging arm. The head is locked in either of two positions by a pin 20 projecting from the head and arranged to engage either one of two openings 22 and 24 which are 180° apart on the under side of the arm. It is apparent that, by turning the hand nut 16, the head can be made to descend until the pin 20 slides out of one of the openings after which the head can be turned until the pin registers with the opposite opening. Thereupon by tightening the hand nut, the head can again be raised to a locked position with the symbols on the type inverted. By this means, the symbols can be faced either way at the end of a comparatively long piece of work. Heretofore, with non-reversible heads, a deep throat opening below the overhanging arm has been needed to receive the work when the symbols were to be inverted. 55

There projects from the bracket 8 a horizontal stud 26 on which is rotatably mounted a plurality of dies in the form of type wheels 28. The stud, in the form shown, is arranged to receive three type wheels which are held in place by a hook 32 engaging a recess 30 in the end of the stud, the hook being formed on a swinging latch 34 pivoted to a stud 36 above the type wheels. The hook is held in locked position by a spring pressed detent 38 housed in a recess of the swinging latch. Around the interior of each type wheel is a series of notches 40 arranged to be engaged by a spring-pressed locking plunger 42 in a recess of the stud 26. For turning the type wheels to select the characters to be printed, a gear wheel 44 is fixed to a rod 46 which is slidably and rotatably mounted in a bracket on the head so that the gear can be slid into engagement with any one of the type wheels and then turned to select the character desired. In an opening at the lower end of the bracket

8 there is secured a single stamp 48 having any desired character lying in line with the lowermost type on the type wheels.

The type on the type wheels form a pressure receiving member which is normally fixed and a movable pressure applying member cooperates with the first member and is in the form of a work table 50 having a substantially cylindrical stem 52 slideable in a sleeve 54 which, in turn, is slideable to a slight extent in the casing 56 projecting from the frame. The sleeve has a coned opening 58 the conical surface of which rests upon a cone-pointed screw 60, the latter being adjustable in order to vary the initial position of the sleeve for a purpose which will appear later. The sleeve 54 has circular vertical openings housing springs 62 which normally tend to urge the work table 20 upwardly to carry a piece of work against the type wheels. In the stopped position of the machine, however, the upward movement of the table under the influence of the springs is prevented by a pin 64 passing through a lost motion slot 66 in the stem 52 and entering a slot 68 in the sleeve. The pin engages the stem at the lower end of the slot 66 and holds the stem down, there being a link 70 joined to the pin and having its lower 30 end bifurcated as at 72 to embrace a block 74 on a crank pin 76. The link 70 has a vertical recess receiving a spring 78 interposed between the bottom of the recess and the block 74 so that when the block rises, the upward thrust is a yielding one. The block 74, however, engages a block 80 connecting the arms of the bifurcated link and holds the link, the pin, the stem and the table down when the machine is stopped. The pin 64 is 40 also connected to a block 82 slideable in a cut-out portion of the stem 52 and having an inclined cam face 84 arranged to engage a cylindrical roll 86 extending across a recess in the stem and entering two opposite horizontal slots 88 in the sleeve 54.

When the machine is started, the link 70 is released by the block 74 and the upward movement of the pin 64 allows the springs 62 to force the work table upwardly to grip a piece of work against the type. This action is a yielding one and results in a substantially uniform pressure on the work whatever its thickness may be. When the movement of the work table is thus arrested, the pin 64 and the block 82 continue to rise, carrying the inclined face 84 against the roll 86 and moving said roll horizontally until it engages an inclined face 90 on the stem 52. At this point the roll jams or locks the stem and sleeve together after which the spring 78 yields until a roll 92 on the crank pin 76 comes into engagement with a surface 94 on the under side of the sleeve 54. The sleeve and stem and work table being locked together by the roll, the table must

rise a predetermined distance which depends upon the initial position of the sleeve and the travel of the roll 92 after it engages said sleeve. As above stated, the initial position of the sleeve can be varied by turning the cone-pointed screw 60 in or out. Thus there is a definite upward movement of the table after the work has been clamped between the work table and the dies and consequently the depth of the impression for a given line of work is constant and independent of the thickness or degree of hardness of the material. An edge gage 96 is formed on the end of a rod 98 which is slideable in a bearing of the frame and clamped in any desired position by a clamp screw 100.

Although the invention has been described with special reference to stamping, it is not, in its broader aspects, necessarily limited to this operation.

Having described our invention, what we claim as new and desire to secure by Letters Patent of the United States is:

1. A stamping machine having, in combination, a frame, stamping dies carried by the frame, a work table, springs for causing relative movement of approach between the work table and the dies to clamp a piece of work yieldingly, and means for thereafter causing relative movement of the dies and the work table through a predetermined distance to effect an impression.

2. A stamping machine having, in combination, a frame having an overhanging arm, a plurality of rotary stamping dies normally held in a fixed position on the overhanging arm, a work table, means for raising the work table yieldingly to clamp work pieces of different thicknesses with the same pressure against the dies, and means for thereafter raising the work table positively a definite distance to effect an impression of predetermined depth.

3. A machine of the class described having, in combination, a pair of coacting pressure members adapted to receive between them work pieces of different thicknesses, a hollow guide for one of said members, springs between said guide and one of said members for normally urging one of said members toward the other member, means for controlling the action of said springs to effect a preliminary work clamping movement, and means for subsequently causing additional relative movement of said members to apply pressure to the work.

4. A machine of the class described having, in combination, a fixed pressure receiving member and a movable pressure applying member adapted to receive between them work pieces of different thicknesses, a hollow guide for the movable member, means for normally urging said movable member toward the fixed member, means for controlling the action of said means to ef-

fect a preliminary work clamping movement of the movable member, means for locking said guide to the movable member, and means for subsequently causing a pressure applying movement of said guide and movable member.

5. A machine of the class described having, in combination, a fixed pressure receiving member, a movable pressure applying member, springs for yieldingly moving said movable member toward the first member to effect a preliminary work clamping movement, means for controlling the action of said springs, means for subsequently causing a pressure applying movement of the movable member through a definite distance, and means for varying said distance.

6. A machine of the class described having, in combination, a fixed pressure receiving member, a work table slidable toward the member, means for preliminarily moving said table toward the member to grip a piece of work, a slidable member for guiding the table, means for locking the table to the slidable member, and means engaging said slidable member after the locking action to cause a positive movement of said table.

7. A machine of the class described having, in combination, a fixed pressure receiving member, a work table slidable toward the member, means for moving said table towards the member to grip a piece of work, a slidable member for guiding the table, means for locking the table to the slidable member, means engaging said slidable member after the locking action to move said table a predetermined distance, and means for varying the initial position of the slidable member to vary said predetermined distance.

8. A machine of the class described having, in combination, a fixed pressure receiving member, a work table having a slidable stem, a sleeve surrounding the stem, means for urging the table away from the sleeve toward the fixed member, means for controlling the action of said urging means

and locking the stem to the sleeve, and means for moving the sleeve and the table 50 together.

9. A machine of the class described having, in combination, a fixed pressure receiving member, a work table having a slidable stem, a sleeve surrounding the stem, means 55 for yieldingly moving said table toward the member to grip a piece of work, a roll for locking the stem to the sleeve after the work is gripped, and means for moving the sleeve after the locking action to cause a positive 60 movement of the table.

10. A machine of the class described having, in combination, a fixed pressure receiving member, a work table having a slidable stem, a sleeve surrounding the stem, springs 65 for urging the table away from the sleeve toward the fixed member, a roll extending through said stem and having its ends engaging said sleeve, a block slidable in said stem and having a cam surface engageable 70 with said roll, means for moving said block to cam the roll against the stem and lock the latter to the sleeve, and means engaging the sleeve for causing a positive movement of the work table after the locking action. 75

11. A machine of the class described having, in combination, a fixed pressure receiving member, a work table having a slidable stem, a sleeve enclosing the stem, springs for urging the table away from the sleeve to 80 toward the fixed member to clamp a piece of work, a roll extending across said stem and having its ends rolling in slots in the sleeve, a block slidable in said stem and having a cam surface engageable with said roll, an 85 inclined face on said stem in the path of the roll, means for moving said block to cam the roll against the inclined face of the stem to lock the stem and sleeve together, and means engaging the sleeve for causing 90 a positive movement of the work table after the locking action.

In testimony whereof we have signed our names to this specification.
